* cited by examiner

Primary Examiner — Melanie H Tung(74) Attorney, Agent, or Firm — Sterne, Kessler, Goldstein & Fox P.L.L.C.(57) CLAIM

The ornamental design for a display screen or portion thereof with icon, as shown and described.

DESCRIPTION

The FIGURE is a front view of a display screen or portion thereof with icon showing my new design.

The broken lines around the FIGURE show a display screen or portion thereof, and form no part of the claimed design.
